Primary Examiner — Susan Bennett Hattan*Assistant Examiner* — Marie Fast Horse(74) *Attorney, Agent, or Firm* — RatnerPrestia(57) **CLAIM**

We claim the ornamental design for an ear scanner, as substantially shown and described.

DESCRIPTION

FIG. 1 is a front isometric view of an ear scanner;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back isometric view thereof.

The broken lines on the power button seen in FIGS. 1, 2, 4, and 6 depict environment and form no part of the claim, while the broken lines in FIGS. 3, 5, and 8 depict portions of the ear scanner that form no part of the claimed design.
